UNITED STATES PATENT OFFICE.

WILLIAM H. CLARK, WILLIAM J. CLARK, AND ANSON O. KITTREDGE, OF SALEM, OHIO, ASSIGNORS TO THE KITTREDGE CORNICE AND ORNAMENT COMPANY, OF SAME PLACE.

IMPROVEMENT IN MACHINES FOR MAKING SHEET-METAL MOLDINGS.

Specification forming part of Letters Patent No. 171,917, dated January 11, 1876; application filed October 4, 1875.

CASE A.

To all whom it may concern:

Be it known that we, WILLIAM H. CLARK, WILLIAM J. CLARK, and ANSON O. KITTREDGE, of Salem, in the county of Columbiana and State of Ohio, have invented a certain new and Improved Machine for Making Sheet-Metal Moldings for Arches, of which the following is a full, clear, and complete description, reference being had to the accompanying drawings making part of this specification, in which—

Figures 1 and 2 are side and end views of the machine. Fig. 3 is a plan view.

Like letters of reference refer to like parts in the several views.

This invention is for making arched sheet-metal molding for window and door caps, and other arch-moldings, and which consists of a pair of dies, male and female, co-operating in combination with a pair of guides, arranged one on each side of the dies, whereby the curvature of the arch is maintained while the same is being passed between the dies for having the molding formed thereon.

Of the construction of the above said machine and its practical working the following is a more full description.

In the drawings, A represents a base or block, whereon is secured a die, B, by means of a slotted standard, C, in the slot of which the die is held and secured by a screw or bolt, D.

It will be seen that said die consists of a thin plate of metal, in the upper edge of which is formed the profile or contour of a certain style of molding, as shown at b, Fig. 2.

The die B referred to is the lower one. A corresponding upper one is shown at E, which also consists of a thin plate of metal, and is arranged directly in a right line above it, so that it may co-operate therewith on the sheet for forming the molding. On each side of the die B is arranged guides, F G, or their equivalents for the same object and result. Said guides consist of thin plates of metal, similar to the dies E and B, and having in their upper edge or face a form of molding like that in the face of the die B, as will be seen at b'.

The guides referred to are held in position by a clamp, H, and secured therein by a bolt, c. The stem of the clamp consists of a screw, I, forming a standard whereby the guides are secured in the base by being screwed into jam-nuts J K, one above the base and one below, as will be seen in Fig. 1.

By means of the jam-nuts the guides can be easily and readily adjusted in their relation to the die B as to height and angle, for a purpose presently shown. The following is a description of the practical operation of the machine.

As above said, this machine is for forming the moldings in sheet metal for arches—as, for instance, windows and doors which have arched caps, and for other purposes requiring arching moldings. To this end a piece of sheet metal is cut to the required curve for the arch, the curvature of which may be more or less, as the nature of the work may demand. This being done the two guides F G are then so adjusted in their relation to the die B as to form two radii of a circle, or they may be adjusted to curved lines, of which the piece of metal referred to may be a segment or arc. The guides, when thus adjusted, are shown in Figs. 1 and 3, in which it will be seen that the guides on either side of the die are not parallel therewith; but which, together with the die B, form three sections of radial lines, and which may be supposed to be the radii of the circle or other curve, of which the piece of metal for the arch is a segment.

In order to form the moldings on the segment referred to, one end thereof is laid upon the face of the die B under the die E, and permitted to rest on a guide at the side. The upper die is now made to strike down upon it with light rapid strokes, or rather by compressive strokes than by sharp percussive blows, thereby conforming the metal to the shape of the face of the dies, as it is passed along between them, not wholly at the first pass, but by repeated passes, as the thickness of the metal or the style of the molding may render it necessary. As the metal passes be-

tween the dies the partially-formed curves and angles of the molding will fit in the face of the guides, and prevent the metal from lateral movement while being acted upon by the dies; also, in consequence of the radial relation of the guides to the segmental curve of the metal they guide it along in its curvilinear course between the dies. Hence, forming the moldings on the metal will not change its segmental curve, so that any number of pieces required to make up the entire arch will be exactly alike, and therefore can be put together without trouble of fitting the ends, so as to conform to the curves and angles constituting the members of the moldings; also to the curvature of the arch.

Whatever the arch may be as to its degree of curvature the guides can be easily and readily adjusted in their radial relation to the die, so as to form radii of such curve; hence, arches of any desired degree of curvature can be made by this machine. By using these narrow and thin dies we are enabled to turn quick curves, even with profiles having large members—a thing very difficult to do by other means.

The side guides, by means of adjusting screws and nuts connected therewith, as shown, allow said guides to be adjusted either above or below the die B, as may be expedient. This

vertical adjustment of the guides admits of moldings being made up of a hoop and cylindrical form, or in sections thereof. This is done by arranging the guides and die B parallel with each other, or nearly so, and then moving the guides, either above or below the die B, to the desired point, as may be required for the diameter of the cylindrical moldings.

The upper die is operated by being fixed in the head of a power-hammer actuated by a cam, so that the die may not fall so suddenly or decidedly as when actuated by a trip in the ordinary way. A more compressive action of the die thereby is obtained on the metal. The construction of the hammer and general operation are similar to the ordinary power-hammers in use, or may be simply a modification of them.

What we claim as our invention, and desire to secure by Letters Patent, is—

The adjustable guides F G, in combination with the die B, substantially as described, and for the purpose set forth.
